(57) **CLAIM**

The ornamental design for a circuit breaker face, as shown and described.

DESCRIPTION

FIG. 1 is an isometric view of a circuit breaker face showing my new design;

FIG. 2 is a front elevation view thereof.

FIG. 3 is a bottom plan view thereof.

FIG. 4 is a left side elevation view thereof.

FIG. 5 is a top plan view thereof.

FIG. 6 is a right side elevation view thereof; and,

FIG. 7 is a rear elevation view thereof.

The broken lines are for illustrative purposes only and form no part of the claimed design.
